UNITED STATES PATENT OFFICE

THOMAS W. SATTERTHWAITE, OF NEW YORK, N. Y., ASSIGNOR TO HAMILTON FISH
BENJAMIN AND JAMES D. PELL, BOTH OF NEW YORK, N. Y., AND RICHARD ELY, OF
SHORT HILLS, NEW JERSEY

PACKAGE

Application filed October 24, 1930. Serial No. 490,841.

This invention relates to improvements in merchandise containers, and more particularly, to improvements in containers for distribution of coffee, sugar, tobacco and similar commodities, to consumers.

It is a general object of this invention to provide a package which may be readily sealed so as to protect the contents thereof from atmospheric conditions and deterioration.

Another object of the invention is to provide a package which is substantially airtight so that the contents thereof may be vacuum sealed and maintained in such condition indefinitely.

Still another object of the invention is to provide a novel closure for a package of this type.

Still another object is to provide a merchandising package whereby the merchandise may be packed in an improved manner both from an economic and selling standpoint.

Other objects of the invention will be in part pointed out in the following detailed description of the preferred embodiment of the invention, and will be in part obvious as the description proceeds.

A feature of the invention resides in a method of folding a package from a blank of novel shape, the particular method of folding resulting in a construction which may be readily glued and sealed to form an air-tight package.

Another feature of the invention resides in a novel means of closing the package, which comprises folding the upwardly extending sides in a plurality of accordian folds or pleats, providing clamping means for tightly compressing the lines of fold and also using a filler strip which may be withdrawn, thereby releasing the pressure on the folds and permitting the clamping means to be readily removed.

The invention accordingly comprises an article of manufacture possessing the features, properties, and the relation of elements which will be exemplified in the article hereinafter described and the scope of the

application of which will be indicated in the claims.

For a more complete understanding of the nature and objects of the invention, reference is had to the accompanying drawings wherein:

Fig. 1 is a blank of material from which the merchandising container is to be formed;

Fig. 2 illustrates the container during one stage of the folding process;

Fig. 3 illustrates the container during another stage of the folding process;

Fig. 4 is a finished container;

Fig. 5 is an exploded view in perspective showing means for sealing the container;

Figs. 6 and 7 are transverse sectional views showing the relation of two types of filler strips with reference to the sealing clamp and the sealing folds; and

Fig. 8 shows one embodiment of a filler strip.

In the drawings, wherein the same numerals refer to corresponding parts, a blank 10 is shown of material from which the package is to be folded. This blank may be made of any suitable material, such, for example, as paper, cloth and tinfoil, but it is particularly suitable for such material as cellophane, as the sealing means which is used with the preferred embodiment of the invention is particularly applicable to this last mentioned substance. The finished package will have suitable dimensions, the length of which has been indicated by the letter *a*, the width by the letter *b*, and the depth by the letter *c*.

The blank 10 will, therefore, be proportioned so as to have a base portion 11 having the dimensions *a* and *b* with sufficient material extending from the edges of this base portion to provide walls of the package having the height *c*. Thus, the length of the blank 10, which is the dimension running parallel to dimension *a*, will have a length corresponding to *a* plus twice the length *c*. The width of the blank will be equal to *b* plus twice the length *c*. Thus, in the finished product, the bottom of the package will be the portion 11 bound by the dotted lines 16a, 17a, 18b and 19b. The sides of the package 16 and 17 are bound respectively by dotted lines 16a, 16c, 100

13 and 17a, 17c and 15, and the ends of the package 18 and 19 are bound respectively by the dotted lines 18b, 18c and 19c. Extending laterally from the longer edges of the blank 5 between the dotted lines 16c and 17c are respectively flaps 12 and 14, which are adapted to be folded along the dotted lines 13 and 15, for a purpose which will be hereafter described. From each corner of the base portion 10 of the blank bounded by the dotted lines 16c and 18c, 17c and 18c, 17c and 19c, 16c and 19c will be referred to as common 15 extensions of the side and end sections.

It is to be understood that the blank need not necessarily be marked out in this way, the dotted lines merely indicating lines of fold in order that the way in which the package 20 is constructed may more readily be described.

In constructing the package, the blank is first folded along the lines 18c—16a—19c and 18c—17a—19c, as indicated in Fig. 2, thus 25 bringing the sides 16 and 17 in their proper relative positions. The ends of the package are then formed by folding along the lines 18b and 19b until the ends 18 and 19 come in position with the lines of fold 16c coinciding 30 with 18c, and 17c coinciding with 18c at one end, and 16c coinciding with 19c, and 17c coinciding with 19c at the other end. During this folding process, the corners of the blank or side and end extensions 21 are also 35 folded along the diagonal 20, this corner portion extending exteriorly of the container as shown in Fig. 3. These corner portions 21 are folded back along the corner edges c of the container until they come in contact with 40 the side portions thereof. The corner portions at one end of the container will, under the circumstances shown, fold over the corner portions adjacent the other end, as shown in Fig. 4, and in accordance with this invention 45 these portions may be held in position by suitable means, as, for instance, a seal 22 which may be glued or otherwise held in position.

A preferred embodiment of the invention 50 has been shown wherein the proportions are such that the corner portions 21 will overlap each other, although the invention is not to be limited in this regard, as any proportions could be used and if overlapping should not occur, the corner portions could be glued directly to the side walls of the container, either by gluing along the lines of fold 20 or by a plurality of seals. In the preferred 55 embodiment of the invention shown, the corner portions may also be glued along the lines of fold 20 to hold them in position.

The extension flaps 12 and 14 which are a continuation of the sides 16 and 17 are folded back along the lines 13 and 15 over the sides 60 of the container to engage and hold in posi-

tion the upper edges of the refolded corner portions 21. This is shown in Figs. 3 and 4. This flap may be suitably held in position as by gluing, so that all of the folds of the resultant container are substantially air-tight. 70

Figs. 5, 6, 7 and 8 illustrate a novel means for sealing a container after filling. The sides 30 and 31 of the container are brought together and fluted with a plurality of accordion folds, as at 32. It will be noted that 75 the sides 30 and 31 of the bag are in close contact along the lines of fold 33 and 34, so that if these folds are tightly clamped, a seal will be present along each of the lines of fold. As many of these accordion folds as 80 desired may be used. In order to maintain the seal, it is preferred to use a clamp 35 of suitable material which has rebent edges 36 and 37 extending longitudinally of the accordion folds and adapted to engage under the folds, 85 and clamped as shown in Figs. 6 and 7 to tightly grip and compress the folds along the lines of fold 33 and 34. This clamp may be made of metal, celluloid or any other suitable material which will fulfill the desired 90 function. Between the surface of the clamp 35 and the upper surface of the topmost fold is a filler strip 38, co-extensive with the clamp 35 and having suitable means at the end thereof, as for instance a grip 39 which just 95 protrudes beyond the end of the clamp 35 to facilitate gripping and withdrawing it from position. When the package is sealed, the filler strip 38, together with the clamp 35, contacts to secure the accordion folds tightly in 100 position. However, when it is desired to open a package, the filler strip may be easily withdrawn by pulling on the grip 39. When the filler has been withdrawn, the clamp 35 105 may be easily removed by sliding it longitudinally of the folds and the package opened.

Should it not be desirable to use all the 110 contents of the package at one time the accordion folds may be refolded and the clamp reapplied. This will be sufficient without insertion of the filler to keep the package closed so as to prevent spilling of the contents therefrom.

Another type of filler strip is shown in 115 Fig. 8. In this instance, a bifurcated strip, having arms 40 and 41 and a grip 42, is shown which is adapted to be held in position between the rebent portions 36 and 37 of the clamp 35 and the under surface of the accordion fold adjacent the body of the package. The position of this filler strip with 120 reference to the folds and the clamp is shown in Fig. 7. It functions in the identical manner as the filler strip 38 heretofore described. These filler strips may be made of metal, 125 cardboard, wood, paper, or any other suitable substance.

A sealing device of this type is particularly 130

desirable, especially when the package consists of material such as cellophane.

Since certain changes may be made in the above article and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:—

20. 1. A merchandise container having extensions adapted to form a closure when pleated, sealing means tightly engaging the folds of said pleated extensions, and removable means positioned adjacent said extensions co-acting with said sealing means to release said folds when removed.

2. A merchandise container having extensions adapted to form a closure when pleated, sealing means comprising a clamp and a filler 30 strip co-acting to engage intimately the folds of said pleated extensions, said filler strip being removable to release the engagement of said clamp with said folds.

3. A merchandise container having extensions adapted to form a closure when pleated, sealing means comprising a clamp and a filler strip co-acting to engage intimately the folds of said pleated extensions, said filler strip being removable slidably whereby the degree of 40 intimate engagement between said clamp and said folds is reduced.

4. A merchandise container having extensions adapted to form a closure when pleated, sealing means comprising a filler strip positioned adjacent the upper fold of said pleated extensions and a clamp retaining said filler strip in position and the folds of said pleated extension in intimate contact, said filler strip being adapted to be removed slidably to permit disengagement of said clamp from the 50 pleated extensions.

5. A merchandise container having extensions adapted to form a closure when pleated and sealing means comprising a clamp having rebent portions, a filler strip positioned between said rebent portions and the folds of said pleated extensions, said clamp functioning to compress the pleated folds in intimate engagement along the lines of fold, 60 said filler strip being slidably removable to facilitate removal of said clamp.

6. A merchandise container having extensions adapted to be folded to form a closure, clamping means for retaining said folded extensions, and a slidable wedging element

adapted to be inserted between the clamp and the folded extensions to hold the latter in intimate relation.

In testimony whereof I affix my signature.

THOMAS W. SATTERTHWAITE.
